SAFETY CHOCK FOR RAILROAD ROLLING STOCK

Jay Everett Livengood, Mona, W. Va.

Application March 11, 1942, Serial No. 434,294

4 Claims. (Cl. 104—258)

This invention relates to a safety chock for railroad rolling stock to eliminate accidents caused by runaway rolling stock left unattended on tracks, and is especially adapted for use on track sidings or on tracks in mines and similar places.

The primary object of this invention is the provision of a device of the above stated character which may be easily and quickly installed any place desired on a track as either a temporary or permanent fixture and may be readily operated to assume operative or inoperative positions and when operative it will efficiently chock a car or other rolling stock from moving by gravity and when inoperative will be entirely clear of the rolling stock or the movement thereof over the track.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a top plan view illustrating the application of a safety chock to a rail of a railroad track and constructed in accordance with my invention.

Figure 2 is a longitudinal sectional view showing the device applied to a rail and in an inoperative position.

Figure 3 is a view similar to Figure 1 with a cover element removed and showing the device in an operative position.

Figure 4 is a view similar to Figure 3 showing the device in an operative position.

Figure 5 is a transverse sectional view showing the device in an operative position with a wheel of rolling stock in engagement therewith.

Figure 6 is a transverse sectional view taken on the line 6—6 of Figure 4.

Figure 7 is an end elevation illustrating the operating hand lever of the device.

It is preferable that the present invention be adapted to the outside rail of a track and any place along the track where it may be desired to secure a car or similar device against accidental movement. The drawings in Figures 1 to 4, inclusive, clearly illustrate the application of the invention, the outside rail of the track being indicated by the character 5.

An elongated horizontally arranged base 6 is provided and the width of a portion thereof is such that the base may be fitted between a pair of supporting ties for the rail 5 and underlie the

latter. Detachable clamps 7 are located on one end of the base to engage the inside of the rail 5 above the base thereof. The clamps 7 have serrated faces 8 to obtain a firm grip on the rail. The base is provided with a chamber 9 extending substantially the full length thereof and from Figure 4 it will be seen that the chamber extends under the base of the rail.

Spaced guide members 10 are formed on the base 6 to engage with the opposite sides of the rail 5 from the clamps 7. The guide members 10 are undercut, as shown at 11, to permit the base of the rail to extend thereunder. The guide members 10 are provided with inclined or cam faces 12.

A chock member 13 is slidable in the chamber 9 and has integral therewith a chock head 14 provided with a shouldered portion 15 and guide engaging portions 16 adapted to ride upon the faces 12 of the guide members 10 in order that the latter may bring the chock head in a position of overlying the tread portion of the rail on the movement of the chock member 13 into an operative position. The ball of the rail fits snugly within the shouldered portion 15 of the chock head.

The chock member 13 is provided with a bifurcation 17 defining a tongue 18 adapted to move under the base of the rail on the chock head assuming an operative position with respect to the rail and coacts with the portions 16 and the guide members 10 in preventing tilting of the chock head when engaged by a wheel of a car or similar device.

In Figures 1, 3 and 4 of the official drawings the chock member and its head 14 is disclosed in operative position with respect to the rail. In Figure 2 the chock member 13 is disclosed as being in an inoperative position with the chock head positioned a sufficient distance from the rail so as not to interfere with the movement of car wheels thereover.

The chamber 9 opens outwardly through the top face of the base 6 and a portion thereof is closed by a removable cover 19.

A pitman 20 is pivotally connected to the chock member 13 and is slidably supported in the chamber 9 by a member 21 carried by the base. A portion of the chamber 9 is enlarged to accommodate a pivotally mounted bell crank lever 22. Pivoted to one end of the bell crank lever 22 is a link 23 which is in turn pivotally connected to the pitman 20. The other end of the bell crank lever 22 has a pin and slot connection 24 with a link 25. The link 25 is journaled

on a crank 26 of an operating shaft 27 journaled in a bearing 28 mounted on one end of the base 6. An operating lever 29 provided with a hand grip 30 is journaled on the shaft 27 and is retained thereon by a pin 31 operable between spaced lugs or shoulders 32 formed on the lever 29. The lugs 32 and pin 31 will permit the lever to have a limited movement or rotation on the shaft 27 before the latter will be rotated by said lever 29, the purpose of which is to permit the lever 29 to assume a horizontal position when the chock member 13 is either in operative or inoperative position.

With the lever 29 in either of its horizontal positions it will be less apt to be contacted by rolling stock passing along the rail.

A coil spring 3 surrounds the pitman 20 and is interposed between the link 23 and the bearing 21. The purpose of the spring 33 is to urge the chock member 13 into an inoperative position and to sustain said chock member 13 in an operative position some suitable fastening means (not shown) may be provided on the base 6 to secure the lever 29 in its horizontal position.

Whenever it is desired to chock a car on the track, the lever 29 is operated, imparting to the chock member 13 sliding movement and as the chock member slides in the direction of the rail the chock head is guided upwardly and over the ball of the rail so as to come in the path of a wheel of the car and when engaged with the wheel will prevent the car from rolling from a set position. The lever 29 then may be fastened in its horizontal position by the locking means (not shown). When it is desired to free the car of the action of this device, the operating lever 29 is swung in an opposite direction to assume a horizontal position permitting the spring 33 to slide the chock member 13 in a reverse direction which positions the head 14 clear of the rail.

This device may remain attached to the rail for an indefinite period of time or it may be used in a portable way, that is applied and removed to the rail of a track whenever it is desired to chock a car.

While I have shown and described the preferred embodiment of my invention, it will be understood that minor changes in construction, combination and arrangement of parts may be made without departing from the spirit and scope of the invention as claimed.

Having thus described the invention, what I claim is:

1. In a safety chock, an elongated base to extend under a rail of a track, guide members formed on said base to engage one side of the rail and having inclined faces, clamps on said base coacting with said guides in releasably securing the base to the rail, a chock member slidable on the base and movable over the inclined faces of the guides to assume operative and inoperative positions with respect to the rail, means on said chock member to engage under the rail and coact with the guide members in preventing movement of the chock member when in operative position with respect to the rail and under the influence of a car wheel, and an operating means connected to the chock member.

2. In a safety chock, an elongated base to extend under a rail of a track, guide members formed on said base to engage one side of the rail and having inclined faces, clamps on said base coacting with said guides in releasably securing the base to the rail, a chock member slidable on the base

and movable over the inclined faces of the guides to assume operative and inoperative positions with respect to the rail, means on said chock member to engage under the rail and coact with the guide members in preventing movement of the chock member when in operative position with respect to the rail and under the influence of a car wheel, a pitman slidable on the base and pivotally connected to the chock member, a bell crank lever pivoted on the base and pivotally connected to the pitman, a spring acting on the bell crank lever to normally position the chock member in an inoperative position with respect to the rail, and an operating means connected to the bell crank lever.

3. In a safety chock, an elongated base to extend under a rail of a track, guide members formed on said base to engage one side of the rail and having inclined faces, clamps on said base coacting with said guides in releasably securing the base to the rail, a chock member slidable on the base and movable over the inclined faces of the guides to assume operative and inoperative positions with respect to the rail, means on said chock member to engage under the rail and coact with the guide members in preventing movement of the chock member when in operative position with respect to the rail and under the influence of a car wheel, a pitman slidable on the base and pivotally connected to the chock member, a bell crank lever pivoted on the base and pivotally connected to the pitman, a spring acting on the bell crank lever to normally position the chock member in an inoperative position with respect to the rail, a crank shaft journaled on the base, a link connecting the crank of the crank shaft to the bell crank lever, an operating lever journaled on the shaft, spaced lugs on the lever, a pin connected to the shaft and operating between the lugs and coacting therewith in establishing a drive between the lever and the shaft and adapted to permit the lever to assume a horizontal position when the chock member is in either operative or inoperative position.

4. In a safety chock, an elongated base to extend under a rail of a track, guide members formed on said base to engage one side of the rail and having inclined faces, clamps on said base coacting with said guides in releasably securing the base to the rail, a chock member slidable on the base and movable over the inclined faces of the guides to assume operative and inoperative positions with respect to the rail, means on said chock member to engage under the rail and coact with the guide members in preventing movement of the chock member when in operative position with respect to the rail and under the influence of a car wheel, a pitman slidable on the base and pivotally connected to the chock member, a bell crank lever pivoted on the base and pivotally connected to the pitman, a spring acting on the bell crank lever to normally position the chock member in an inoperative position with respect to the rail, a crank shaft journaled on the base, a link connecting the crank of the crank shaft to the bell crank lever, an operating lever journaled on the shaft, spaced lugs on the lever, a pin connected to the shaft and operating between the lugs and coacting therewith in establishing a drive between the lever and the shaft and adapted to permit the lever to assume a horizontal position when the chock member is in either operative or inoperative position, said chock member including a head portion cut away to define angularly related shoulders to engage with the rail.

JAY EVERETT LIVENGOOD.
